DESIGN FOR A TEXTILE FABRIC

Jean Aemisegger, Bergenfield, N. J., assignor to
The American Fabrics Company, Bridgeport,
Conn., a corporation of Connecticut

Application December 20, 1933. Serial No. 50,139

Term of patent 3½ years

To all whom it may concern:

Be it known that I, JEAN AEMISEGGER, a citizen of the United States, residing at Bergenfield, county of Bergen, and State of New Jersey, have invented a new, original, and ornamental Design for a Textile Fabric, of which the following is a specification, reference being had to the accompanying drawing, forming part thereof.

The figure is a plan view of a piece of textile fabric embodying my new design.

The cross hatched portions appearing on the disclosure of the drawing are merely to indicate the body of the fabric.

I claim:

The ornamental design for a textile fabric, substantially as shown and described.

JEAN AEMISEGGER.
